(57) **CLAIM**

The ornamental design for a hood for a backpack, as shown and described.

DESCRIPTION

FIG. 1 is a perspective view of a hood for a backpack in an open condition, showing my new design.

FIG. 2 is a front view of the hood for a backpack of FIG. 1 in an open condition;

FIG. 3 is a rear view of the hood for a backpack of FIG. 1 in an open condition;

FIG. 4 is a right-side view of the hood for a backpack of FIG. 1 in an open condition;

FIG. 5 is a left side view of the hood for a backpack of FIG. 1 in an open condition;

FIG. 6 is a top view of the hood for a backpack of FIG. 1 in an open condition;

FIG. 7 is a top view of an alternate embodiment of the hood for a backpack of FIG. 1 in a closed condition with the hood folded inside a zippered collar thereof;

FIG. 8 is a bottom view of the hood for a backpack of FIG. 7 in a closed condition with the hood folded inside the zippered collar thereof;

FIG. 9 is a rear view of the hood for a backpack of FIG. 7 in a closed condition with the hood folded inside the zippered collar thereof;

FIG. 10 is a right-side view of the hood for a backpack of FIG. 7 in a closed condition with the hood folded inside the zippered collar thereof; and,

FIG. 11 is a left-side view of the hood for a backpack of FIG. 7 in a closed condition with the hood folded inside the zippered collar thereof.

The broken lines showing a backpack are environmental subject matter that forms no part of the claimed design.

1 Claim, 10 Drawing Sheets
